UNITED STATES PATENT OFFICE.

ELLSWORTH A. HAWTHORNE, OF BRIDGEPORT, CONNECTICUT.

LAMP.

1,415,555.

Specification of Letters Patent.

Patented May 9, 1922.

Continuation of applications Serial No. 105,282, filed June 22, 1916, and renewed March 1, 1918, Serial No. 219,869, and Serial No. 149,088, filed February 16, 1917. This application filed April 2, 1920. Serial No. 370,850.

To all whom it may concern:

Be it known that I, ELLSWORTH A. HAWTHORNE, a citizen of the United States, and a resident of Bridgeport, in the county of 5 Fairfield and State of Connecticut, have invented an Improvement in Lamps, of which the following description, in connection with the accompanying drawings, is a specification, like characters on the drawings 10 representing like parts.

This application is a continuation of my co-pending cases Serial No. 219,869, a renewal on March 1, 1918, of an application Serial No. 105,282, filed June 22, 1916, for 15 lamps, and Serial No. 149,088, filed Feb. 16, 1917, for illuminating apparatus.

This invention relates to lamps and more particularly to lamps such as are used on vehicles and one of the purposes thereof 20 is to provide such a lamp which can be readily brought to proper focus.

My invention will be best understood by reference to the following description taken in connection with the accompanying 25 drawings, wherein:

Fig. 1 is a central vertical section partly broken away through a form of lamp which will serve as an illustrative embodiment of my invention;

30 Fig. 2 is a view on a larger scale of the light-carrying member viewed from the top of Fig. 1;

Fig. 3 is a section on line 3—3 of Fig. 2; Fig. 4 is a section on the line 4—4 of 35 Fig. 1, but on a larger scale;

Fig. 5 is a view similar to Fig. 4 showing the parts in a different condition of adjustment;

40 Fig. 6 is a plan view of certain parts arranged in a position similar to those they occupy in Figs. 4 and 5;

Fig. 7 is a section on the line 7—7 of Fig. 1 on the same scale as Figs. 2, 4 and 5; and

45 Fig. 8 is a section through the light carrying member on a horizontal line looking down.

The form of lamp which I have chosen as illustrated in my invention includes a suitable casing with an interior reflecting 50 surface and I have here shown an exterior casing 1 and a separate reflector 3 within the same which may be and preferably is of parabolic form. The front of this casing may be closed by a suitable bezel 5 and glazing 7 here shown as of the kind dis-

closed in my Patent 1,203,618, November 7, 1916. I here show the lamp as carrying a main light 9 disposed centrally therein and a small pilot light 11 disposed at one side thereof. The main light 9 is mounted in 60 a light-carrying member 13 which may be provided, as shown, with suitable bayonet slots 15 to receive pins 17 carried by the light.

The light-carrying member 13, as shown, 65 extends rearwardly through the reflector and preferably to the exterior of the casing 1. Part of the casing 1, presented to the exterior thereof, forms a housing to receive the member 13 and the clamping mechanism 70 therefor and in the present embodiment a part of this housing is extended rearwardly from the main part of the casing and may serve as a handle by which the lamp may be carried and moved. The member 13 is 75 shown as extending through the reflector and through a suitable aperture in the rear of the housing and may be provided exteriorly with a switch handle or finger grip 80 21 it being understood that suitable switch means, such, for example, as those shown in Figs. 1 and 8 and hereinafter more fully described, are carried by the member 13 for controlling the light or lights in the casing.

To adjust the light 9 to proper focus the 85 light-carrying member may be shifted longitudinally in its bearings in the reflector 3 and the housing 19. To permit such adjustment without occasioning rotary movement of the member which would impose a 90 strain on the connecting wires, the member 13 is locked against rotation preferably with the reflector in the manner shown. For this purpose the reflector, which has an opening 95 to receive the member 13, may have a sleeve 23 extending rearwardly therefrom into the chamber formed between the reflector and the exterior casing and the material of this sleeve may be extended at its rear end to 100 form the opposed, inwardly bent lugs 25 100 which are received by slots 27 in the member 13. Otherwise described it might be said that the reflector presents an aperture toward the rear part of the casing and that the material of the wall of said aperture 105 is continued as a lug projecting from the margin of the aperture toward the center thereof and that the light-carrying member fits the aperture with a slot 27 receiving the lug.

It will be apparent that by the construction described, the member 13 and the lamp 9 carried thereby can be adjusted longitudinally but will be held against rotary movement. This construction of the joint provides an extended bearing for the member 13 and permits a wide range of adjusting movement. The form of joint, moreover, can be readily constructed from sheet metal.

10 The adjustment of the light-carrying member may take place from the exterior of the casing by manipulation of the projecting end of the latter. To hold the same in its adjusted position I desirably provide 15 means acting to jam the member in place in the housing 19. These means may take the form shown more particularly in Figs. 1, 4, 5 and 6. The means there shown takes the form of one or more clamping plates 29, two 20 being shown, adapted to fit against the housing at one end and against the light-carrying member 13 at the other. If two plates are used, as in the present embodiment, they are preferably placed opposite one another. 25 These plates are shown in plan view in Fig. 6 and by a comparison with Figs. 4 and 5, it will be seen that their length is greater than the width of the space between the member 13 and the interior surface of the housing. 30 They will therefore be disposed somewhat on a diagonal, as shown in Fig. 1, bracing apart the member 13 and the wall of the housing. Each of these plates 29 is tapped at 31 to receive the screw 33 entering the housing from the exterior thereof so that the plates 29 may be adjusted from the outside. It is apparent that if the screws 33 are turned the diagonal braces 29 will be tilted and act as jaws to grip the member 13 and hold it 35 firmly against lateral movement by exerting a wedging force between the same and the housing 19. In Fig. 4 I have shown the plates gripping part 13 and in Fig. 5 the screws have been manipulated so as to tilt 40 the same away from part 13 and it is apparent that the latter is then released and can be easily moved backward and forward, guided by the lugs 25. If desired the plates may be adjusted in such a manner as to permit 45 voluntary adjustment of the part 13 but so that they will bear upon it in the manner of brake shoes to prevent spontaneous movement. It will be noted that the two parts 29 act somewhat as do the arms of a 50 toggle joint and they might therefore be aptly called toggle arms.

While the toggle arms or gripping jaws 29 are entirely enclosed within the housing 19 and are protected by the same, they are 60 readily accessible for manipulation from the exterior of the lamp by means of the screws 33. Their arrangement is such that they take a very firm grip on the light-carrying member 13 and prevent its longitudinal movement and they are not easily deranged.

on account of the vibration of the vehicle on which the lamp is carried. Furthermore, since they are tightly wedged in place there will be no tendency for them to rattle as is the case with threaded devices. The parts 70 are very simple in construction and readily stamped out of sheet metal.

In the embodiment of the invention shown the light-carrying member 13 also serves as a switch socket and the two lights 9 and 11 75 may be selectively controlled by the handle 21 above described. In the drawing I have shown the duplex cable 35 extending through the exterior casing 1 and comprising the cable 37 leading to the switch and the ground cable 39. From the member 13 the cable 41 extends to the pilot light 11. The finger grip 21 is herein shown as adapted to rotate a plug housed within the member 13 carrying an eccentrically mounted contact member 43 to which is connected the main feed cable 37. Rotative adjustment of the plug is adapted to bring the contact 43 into engagement either with the contact 45 for the main light 9 or the contact 47 with which is 80 connected the cable 41 leading to auxiliary light 11.

An important feature of the construction shown is the ease with which it may be manipulated. For example, it may be supposed that the lamp is used as a so-called spotlight or wind shield light on a vehicle. The finger grip or switch handle 21 provides a means whereby the driver can operate the light as he desires with the fingers of one hand, while the other is left free for controlling the movement of the vehicle. For this purpose the clamping means 29 may be set up so as to prevent too free movement of the light-carrying member but to permit the same to 105 be drawn longitudinally to adjust the focus. It will be noted that the finger grip 21 is permanently mounted in the end of the member 13, or in other words, is fixedly secured to the light socket so that no matter what its position of rotative adjustment it will still serve as a handle to alter the position of the bulb 9 along the reflector axis. The operator is thus enabled by grasping this finger grip to point the light in any 110 direction he desires, to adjust the spread of the rays, and to turn the light on and off, all this being done with the fingers of one hand. Furthermore, in the embodiment shown the cable 35 connects with the member 115 13 laterally in the space between the casing and reflector and therefore remote from the finger grip 21. Thus this grip is entirely unencumbered and the manipulation thereof is facilitated.

I have described in detail the embodiment of my invention here illustrated and in so doing have referred to the various parts by specific words. It will be understood, however, that I have done this in order that the 120 125 130

structure shown might be more readily understood and not with a defining purpose as the various details disclosed are not of the essence.

5. What I do claim and desire to secure by Letters Patent is:

1. A lamp comprising, in combination, a casing embodying an interior reflecting surface and an exteriorly presented housing, 10 a light within said casing and a light-carrying member therefor extending through said housing and mounted for sliding movement whereby to focus said light with respect to said reflecting surface, and means to retain 15 said member in adjusted position comprising a member interposed as a diagonal brace between said light-carrying member and housing and a device for tilting said member.

20. 2. A lamp comprising, in combination, a casing embodying an interior reflecting surface and an exteriorly presented housing, a light within said casing and a light-carrying member therefor extending through 25 said housing and mounted for sliding movement whereby to focus said light with respect to said reflecting surface, and means to retain said member in adjusted position comprising opposed toggle arms interposed 30 between said housing and said member and means to adjust said arms.

35. 3. A lamp comprising, in combination, a casing embodying an interior reflecting surface and an exteriorly presented housing, a light within said casing and a light-carrying member therefor extending through said housing and mounted for sliding movement whereby to focus said light with respect to said reflecting surface, and means to retain 40 said member in adjusted position comprising symmetrically disposed jaws supported by said housing and means accessible from the exterior of the casing to force them against said member to grip the same.

45. 4. A lamp comprising an exterior casing, a housing extending rearwardly from the back thereof and forming a handle for the lamp, a reflector in said casing, a light-carrying member mounted in said housing for 50 non-rotary sliding movement whereby to adjust the focus of a light carried by said member, said member projecting from the rear of said housing for manipulation and means to jam said member into fixed position in said housing after adjustment thereof.

55. 5. A lamp embodying as elements thereof an exterior casing and an interior reflector having aligned openings, a light-carrying 60 member extending through said openings for sliding movement therein and interlocking against rotary movement with one of said elements and means interposed between said member and said casing and adjustable to 65 exert a wedging force tending to move apart

the same, thereby to brace said member in fixed position relative to the wall of the casing.

6. A lamp comprising an exterior casing, a housing projecting rearwardly from the 70 back thereof and forming a handle for the lamp, a reflector in said casing, a light-carrying member disposed in said housing and extending through the reflector and the wall of the casing and joined to one of the same 75 for non-rotary sliding movement whereby to adjust the focus of the light by rectilinear movement of the end of said member which projects through the housing, and means interposed between said member and the wall 80 of the housing between the bearings of the member in reflector and casing, and bearing against said member to hold it fixed against undesired sliding movement relatively to the wall. 85

7. In a lamp, the combination of a casing having a reflecting surface therein, a lamp-focusing and switch-operating handle mounted to turn and move lengthwise of the axis of said reflector and presented exteriorly of said casing, a light source within the casing, a supporting member therefor also embodying a switch, and means to utilize turning movement of said handle to operate said switch and to utilize lengthwise movement of said handle to focus said lamp in all positions of turning movement of said handle. 95

8. A lamp embodying a casing having an interior reflector, a light-carrying member 100 mounted for sliding movement in said reflector but held against rotative movement therein, switch means carried by said member, and controlling means fixedly secured to said member and embodying a rotatable, 105 switch-operating finger grip bodily movable with said casing and presented at the exterior thereof.

9. A lamp embodying a casing having an interior reflecting surface, a light-carrying 110 member extending through the same and mounted for sliding but held against rotative movement therein, switch means carried by said member for controlling the light and a finger grip at the exterior end thereof providing means for rectilinearly moving said member and being rotatable to control said switch means. 115

10. A lamp comprising a casing having an interior reflecting surface, a light source 120 within the casing, a handle presented exteriorly of the casing and connected to said light source to permit focusing adjustment of the latter, electrical connections entering said casing remote from the handle, and 125 switch means therefor under control of the handle for controlling the circuit to the light source, whereby a single unobstructed handle may serve for manipulating the lamp and controlling and adjusting the light. 130

11. A lamp comprising a casing and an interior reflector defining a space between them, a member having bearings in casing and reflector and bridging said space, said member supporting at one end an electric bulb within the reflector and at its other end providing a finger grip exterior to the casing for manipulating the lamp, said grip providing means for moving said member in its bearings to focus the bulb, electric connections entering the space aforesaid and connected to said member and switch means carried by said member under control of said finger grip.
12. A structure as defined in claim 11 with an auxiliary electric bulb having connections to said member and the switch means selectively controlling the circuits to the two bulbs through manipulation of said finger grip.

13. A lamp comprising a casing having an interior reflecting surface, a light-carrying member mounted for sliding, non-rotating movement and projecting to the exterior of said casing, a finger grip rotatably mounted on said projecting end, said grip providing means for sliding said member to focus the light, electric connections secured laterally to said member remote from said grip and switch means carried by said member and controlled by the rotation of the finger grip.

14. A lamp having an interior reflecting surface and an exteriorly presented housing, a light-carrying member extending from the interior to the exterior thereof constructed and arranged for longitudinal adjustment, means within said housing bearing laterally on said member to impede movement thereof and means for adjusting the impeding means to vary the pressure thereof on said member.

15. In a reflecting electric lamp, the combination with a casing; of a reflector in front of the casing, a space intervening between the rear portions of the casing and reflector; an electric lamp bulb; a shell carrying the lamp bulb at its front and movable forwardly and rearwardly to effect focal adjustment of the bulb; a contact carrying plug within the space between the rear portions of the reflector and the casing and coupled with the shell to be movable forwardly and rearwardly therewith in the focal adjustment of the bulb and serving to supply current to the lamp, the plug also being mounted to turn with respect to the shell to cut the lamp in and out of circuit, there being engageable and separable switching contacts in the lamp circuit, one upon the plug; and a forwardly and rearwardly movable and rotatable motion transmitting element connected with and extending rearwardly from the plug and having a gripping head fixed thereto to be movable therewith

and which head is operable from the exterior of the casing to turn said plug to switch the lamp into or out of circuit and to move the plug in or out to move the shell and thereby effect focal adjustment of the bulb.

16. In a reflecting electric lamp, the combination with a casing; of a reflector in front of the casing, a space intervening between the rear portions of the casing and reflector; an electric lamp bulb; a shell carrying the lamp bulb at its front and movable forwardly and rearwardly to effect focal adjustment of the bulb, said shell extending into said space between the rear portions of the reflector and the casing; a contact carrying plug received in the rear portion of said shell and coupled therewith to be movable forwardly and rearwardly therewith in the focal adjustment of the bulb and serving to supply current to the lamp, the plug also being mounted to turn with respect to the shell to cut the lamp in and out of circuit, there being engageable and separable switching contacts in the lamp circuit, one upon the plug; and a gripping head fixedly connected to the plug to be movable therewith and to transmit forward and rearward motion and rotatable motion thereto, which head is operable from the exterior of the casing to turn said plug to switch the lamp into or out of circuit and to move the plug in or out to move the shell and thereby effect focal adjustment of the bulb.

17. In a reflecting electric lamp, the combination with a casing; of a reflector in front of the casing, space intervening between the rear portions of the casing and reflector; an electric lamp bulb; a shell carrying the lamp bulb at its front and movable forwardly and rearwardly to effect focal adjustment of the bulb; a contact carrying plug within the space between the rear portions of the reflector and the casing and coupled with the shell to be movable forwardly and rearwardly therewith in the focal adjustment of the bulb and serving to supply current to the lamp, the plug also being mounted to turn with respect to the shell to cut the lamp in and out of circuit, there being engageable and separable switching contacts in the lamp circuit, one upon the plug; and a forwardly and rearwardly movable and rotatable motion transmitting element connected with and extending rearwardly from the plug and operable from the exterior of the casing to turn said plug to switch the lamp into or out of circuit and to move the plug in or out to move the shell and thereby effect focal adjustment of the bulb.

In testimony whereof, I have signed my name to this specification.

ELLSWORTH A. HAWTHORNE.
